UNITED STATES PATENT OFFICE

2,139,416

FAN

Charles N. McLane, Hyde Park, Mass., assignor
to B. F. Sturtevant Company, Hyde Park,
Boston, Mass.

Application November 20, 1937, Serial No. 175,691

5 Claims. (Cl. 230—114)

This invention relates to centrifugal fans employing adjustable inlet vanes of the type shown by the United States Patent No. 2,063,174, to M. S. Leonard, and relates more particularly to 5 means for preventing foreign matter from being drawn by the action of the fans into the vane adjusting mechanisms.

Centrifugal fans of the induced draft type are commonly used for drawing the flue gases from 10 steam power plants. Where adjustable inlet vanes are used, the vane rotating mechanisms are usually mounted in the fan inlets so as to be exposed to the fluid passing through the inlets. The flue gases from steam plants contain cinders, 15 corrosive gases and other foreign matter which is forced under the pressure created by the fans, to enter the mechanism for rotating the vanes, corroding and clogging same.

According to this invention, clear air is drawn 20 into the vane adjusting mechanism which opposes and prevents the entrance of flue gases and the matter carried by same.

An object of the invention is to prevent the entry of undesirable matter into the vane adjusting mechanism of induced draft fans.

Another and more definite object of the invention is to draw clean fluid into the vane adjusting mechanism of induced draft fans to oppose the entry of unclean fluid.

30 The invention will now be described with reference to the drawing which shows an elevation view in section of a fan embodying this invention.

The fan illustrated has the casing 5 to which is attached the member 6 forming a converging inlet passage which terminates adjacent the fan wheel 7. The wheel 7 is mounted on the shaft 8 which is supported by the bearing pedestal 9. The member 10 encloses the inlet to the fan and forms a passage 19 which communicates with 35 the source of the fluid to be moved by the fan.

The vanes 11 are rotatable to vary the spin of the air entering the fan wheel and are mounted upon the bearings 12 which rotate around pivot rods which extend between the member 6 and the 40 inner portion 13 of a hub member. The outer portion 14 of the hub member is journaled to receive the rotary member 15 which has in its inner portion, a plurality of channels in which the followers 16 attached to the pivot rod bearings 12 extend. The outer portion of the rotary member 15 is formed as a ring gear, the teeth of which mesh with the teeth of the bevel gear 17. The bevel gear 17 is rotated by the shaft 18 which extends to any suitable control point to be rotated manually or under automatic control. The 45

rotary member 15 and the followers 16 function upon rotation of the member 15 to rotate the vanes as described in said Leonard patent.

The fan illustrated may be an induced draft fan and the passage 19 may carry flue gases from 5 a steam power plant to the fan inlet. Such flue gases not only usually contain cinders but also contain corrosive gases such as sulphuric acid gas. These enter the fan inlet and force themselves into the ordinary housings for the vane 10 adjusting mechanisms which are necessarily mounted in the fan inlets, through the several openings through which the pivot rods and control members, etc., extend. The corrosive gases 15 cause corrosion of the device and the cinders collect within the device to hinder its adjustment.

This difficulty is overcome according to this invention by enclosing the mechanism within the housing 20 which in the embodiment illustrated, is an extension of the hub member; by tapping 20 the housing 20 at 21 to receive one end of the pipe 22, and by extending the other end of the pipe 22 through the casing wall 23 into a region of clear air.

The housing 20 is in the path of the flue gases 25 which if the pipe 22 were not provided, would pass through the housing 20 through entering one or more of the several small openings in the housing and through passing out of one or more of the other small openings. The housing 20 is 30 however under sub-atmospheric or negative pressure due to the suction of the fan. The pipe 22 extends at one end into the area of clean air under atmospheric pressure, exterior the fan casing and at the other end into the area of 35 lower pressure at the housing 20. The difference in pressures causes, when the fan is operating, clean air to pass through the pipe 22 into the housing 20 and from the housing 20 through the several small openings previously referred to, 40 into the fan wheel. Thus, when the fan is operating, there is a continuous flow of clean air through the pipe 22 and housing 20 which flow opposes and prevents the flow of flue gases into the housing. 45

While one embodiment of the invention has been described for the purpose of illustration, it should be understood that the invention is not limited to the exact apparatus and arrangement of apparatus illustrated, since many departures 50 may suggest themselves to those skilled in the art without departure from the real invention.

What is claimed is:

1. A fan comprising in combination, a plurality of fan blades, a shaft for supporting said blades, 55

- means forming an inlet passage around said shaft into said blades, a plurality of rotatable vanes in said passage, mechanism in said passage for rotating said vanes, a housing around said mechanism, means forming a passage for connecting said first mentioned passage with a source of gas to be moved, and means connecting the interior of said housing with gas from another source.
2. A fan comprising in combination, a plurality of fan blades, a shaft for supporting said blades, means forming an inlet passage around said shaft into said blades, a plurality of rotatable vanes in said passage, mechanism in said passage for rotating said vanes, a housing around said mechanism, means forming a relatively large passage for connecting said first mentioned passage with a source of gas to be moved, and means forming a relatively small passage connecting the interior of said housing with gas from another source.
3. A fan comprising in combination, a plurality of fan blades, a shaft for supporting said blades, means forming an inlet passage around said shaft into said blades, a plurality of rotatable vanes in said passage, mechanism in said passage for rotating said vanes, a housing around said mechanism, means comprising walls forming a relatively large passage for connecting said first mentioned passage with a source of gas to be

moved, and means forming a relatively small passage extending through one of said walls and connecting the interior of said housing with gas from another source.

4. A fan comprising in combination, a plurality of fan blades, a shaft for supporting said blades, means forming an inlet passage around said shaft into said blades, a plurality of rotatable vanes in said passage, mechanism in said passage for rotating said vane, a housing around said mechanism, means comprising walls forming a relatively large passage for connecting said first mentioned passage with a source of gas to be moved, and a pipe extending through one of said walls and connecting the interior of said housing with gas from another source.

5. A fan comprising in combination, a plurality of fan blades, a shaft for supporting said blades, means forming an inlet passage around said shaft into said blades, a plurality of rotatable vanes in said passage, mechanism in said passage for rotating said vanes, a housing around said mechanism, means forming a passage for connecting said first mentioned passage with a source of fluid to be moved, and means for moving air through said housing in a direction opposing the entry of said fluid into same.

CHARLES N. McLANE.
